UNITED STATES PATENT OFFICE.

ALFRED SHEDLOCK, OF JERSEY CITY, NEW JERSEY.

SPRAY-LAMP.

SPECIFICATION forming part of Letters Patent No. 415,398, dated November 19, 1889.

Application filed July 12, 1888. Serial No. 279,787. (No model.)

To all whom it may concern:

Be it known that I, ALFRED SHEDLOCK, a citizen of the United States, residing at Jersey City, county of Hudson, State of New Jersey, have invented certain new and useful Improvements in Spray-Lamps, of which the following is a specification.

The spray-lamp forming the subject of this application has both the air and oil valves at the point where the air and oil issue from the burner, thus insuring a steady and uniform supply of oil to the flame when in operation and preventing any evaporation and consequent gumming up of the oil when the lamp is out of use. Both the air and oil valves are operated by the same handle, which is so arranged that when it is turned in one direction it first opens the air-valve, and then by further turning in the same direction it opens the oil-valve, and by a reversal of this order of its action the oil-valve is first closed and then the air-valve. This arrangement makes it impossible to throw out a stream of oil, either in the opening or the closing of the valves, before lighting or on extinguishing the lamp. In conjunction with this handle that operates the valves adjusting devices are provided that can be set to allow of the escape of the air and oil in any desired relative proportions to produce the character of flame desired. The relighter is at the upper end of an unbroken tube, which extends to the bottom of the oil-tank. This feature of construction is also carried out in the main oil-pipe and is a very important one in lamps devised for the use of liquid hydrocarbons, as it is difficult to make joints and connections through which such liquids will not penetrate.

In the accompanying drawings, to which I will now refer to more fully explain my improvements, Figure 1 is a central sectional elevation of a spray-lamp made according to my invention. Fig. 2 is an elevation, partly in section, of the upper part of the lamp, taken at right angles to Fig. 1. Fig. 3 is a plan view of the burner with the flame-guard removed. Fig. 4 is a transverse section taken on the line $x-x$, Fig. 2. Fig. 5 is an enlarged view of the relighting device and adjacent parts.

As in other lamps of this class, the oil which is placed in the reservoir a is expelled

under pressure from the inner nozzle 7 into a volume of compressed air passing up around said nozzle, and the mixed air and oil then issue into the combustion-chamber 2 through the nozzle 6 . The nozzle 7 constitutes the upper end of the oil-pipe 8 , which extends down without seam or joint nearly to the bottom of the reservoir a , and the nozzle 6 is secured by means of a screw-thread into the upper end of the stem or body 1 of the burner, which is screwed into the socket b , fastened to the top of the reservoir a . The nozzle 7 is fitted into the nozzle 6 to act as a valve to control the air passing to and through the nozzle 6 , and inside the nozzle 7 is fitted an oil-controlling valve attached to or forming a part of the rod 14 .

In spray-lamps as now made having oil and air valves, each valve is provided with an independent operating-handle, and with the oil under pressure it is imperative that the air-valve be opened first upon lighting a lamp and the oil-valve be closed first upon extinguishing it, and the valves have to be set by trial-adjustment each time the lamp is lighted to produce the flame desired.

Now, one of the leading features of this lamp is the method of actuating both the air and oil valves by means of one handle, causing the air-valve to be opened before the oil-valve when the handle is turned in one direction to start the lamp, and causing the oil-valve to be closed before the air-valve when the handle is turned in the reverse direction to extinguish the flame, and also in causing both the air and the oil valves to be opened to a definite extent each time the handle is actuated in lighting the lamp. The means here shown by which this new method of operating spray-lamps is carried out consists of the cam 9 , rigidly secured to the oil-pipe 8 , and having two cam-slots c and d , the eccentric-pin 10 , projecting inwardly from the body 1 and fitting into the slot c , the pin 12 , projecting from the bearing-piece 13 on the top of the pipe 15 , and passing through the slot d into the vertical guide-groove e formed in the body 1 , the holder 16 , secured to the lower end of the pipe 15 and carrying the rod of the oil-valve 14 , the handle 24 , provided with the adjustable stop 27 and connected to the stem 29 , which is fitted to rotate

in a taper hole in the body 1, and provided at its lower end with bevel-teeth arranged to work into bevel-teeth formed on the cam 9, as shown at Figs. 2 and 4. The cam 9 is provided with a neck which fits into the lower end of the central passage of the body 1, and as there is an equal pressure of air above and below this neck it is only necessary to make an ordinary fit between the neck and body. 5 The neck may be provided with packing-rings, as shown at Figs. 1 and 2. The pin 10 has a taper shoulder seated into a recessed hole formed through the body 1, and is held rigidly therein by means of the hollow screw-plug 11. The part of the pin 10 which extends into the slot *c* of the cam 9 is formed eccentric to the taper shoulder, as shown at Fig. 2. The slots *c* and *d* are partly straight and partly inclined, the straight part of the 10 one being opposite to the inclined part of the other, as clearly shown at Fig. 1, so that when the inclined part of the slot *c* of the cam 9 is being moved over the pin 10 to open the air-valve of the burner the straight part of the slot 15 *d* travels over the pin 12 without moving the oil-valve, which is now closed. Now, when the straight part of the slot *c* moves over the pin 10 the nozzle 7, constituting the air-valve, is held in open position, allowing the air to issue at 20 a uniform rate through the nozzle 6, and the pin 12 is moved down by the inclined part of the slot *d*, thereby opening the oil-valve on the end of the rod 14 in nozzle 7, through the medium of the bearing-piece 13, pipe 15, and 25 valve-rod holder 16. When the cam 9, actuated by the handle 24, has moved the valve on the rod 14 away from its seat in the nozzle 7 sufficiently to allow the right quantity of oil to issue through said nozzle, the stop 27, carried by the handle 24, is set against the lug *e'* 30 on the side of the body 1, and is securely locked in position on the handle by means of the screw 28. The quantity of air passing through the nozzle 6 necessary to insure the 35 perfect combustion and spraying of the oil is governed by the adjustment of the eccentric-pin 10, which when set is clamped in position by the screw-plug 11. The oil-valve rod 14 is screw-threaded at its lower end and passes 40 through a tapped hole in the holder 16, thus enabling the valve to be closed tightly in the nozzle 7 when the pin 12 is in the straight part of the slot *d* of the cam 9. The clamping-screw 17 prevents the rod 14 shifting in the 45 holder 16.

The upper part of the burner comprises the combustion-chamber 2, secured to the top of the body 1 by the outer nozzle 6, the coil of pipe 4, located in the combustion-chamber 50 2, and having its ends bent so as to extend through openings in the sides thereof, and the flame-guard 3, resting on the top of the combustion-chamber and extending down the interior of coil 4. Along the side of the body 1 55 is formed the air-passage *f*, into which the air enters through the inlet-cock 23 from any suitable source of compressed-air supply.

One end of the coil 4 is connected to the upper end of this air-passage, and the other end of the coil is connected to the side branch *g*, 70 which opens into the central passage of the body 1.

Each of the couplings here used for connecting the two ends of the coil to the body of the lamp consists simply of a sleeve 5, fitted 75 by a screw-thread on the coil, the ends of which are made conical to correspond to taper recesses formed in the branches *f* and *g* of the body. The outsides of the sleeves 5 are screw-threaded in opposite direction to their 80 internal threads and fit into correspondingly-tapped holes in the branches *f* and *g* of the body 1. To make these joints, the sleeves 5 are screwed on the ends of the coil 4 after it has been placed in the combustion-chamber 2, 85 and then the sleeves are entered in the tapped holes in the branches *f* and *g*. As the sleeves are now screwed into the branches *f* and *g*, the ends of the coils pass down and extend beyond the sleeves and are ultimately jammed 90 tightly into the taper recesses.

Instead of making the joints between the coil and the body taper in form they may be made flat, and washers used to insure tightness.

The relighting device comprises the asbestos wick *h*, held in the wick-tube 20, which is attached to the upper end of the pipe 19. This pipe 19 passes down, without seam or joint, through the air-passage *f*, nearly to the 95 bottom of the oil-reservoir *a*, and is held at its lower end by a guide-hole formed through the oil-valve holder 16. It is advantageous to supply this relighter with a valve to regulate the supply of oil thereto, and this is done 100 by fitting the pointed plug 21 by a screw-thread into the piece 18, attached to or forming a part of the pipe 19, and providing a seat therefor in the said piece 18. The wick-tube 20 passes through a hole in the bottom 105 of the combustion-chamber 2 and the flange *i* of the body 1. It sets over the upper end of the piece 18, and by means of an internal slot arranged to embrace a pin projecting from the valve 21, it when rotated turns said valve, 110 and so regulates the amount of oil allowed to pass to the wick *h*. The jam-nut 22 on the wick-tube 20, by being set against the flange *i* of the body, makes a tight joint between the lower end of the wick-tube and a flange on 115 the piece 18 and a tight joint between said flange and the top of the air-passage *f*, as clearly shown at Fig. 5.

It is expedient in starting the lamp to first light the relighter, allowing the main flame 120 to be lighted therefrom when the air and oil are turned on. To provide for this, I make an opening *j* through the side of the combustion-chamber in proximity to the wick *h*, through 125 which opening a light may be readily applied to the wick. This opening is closed by the cover *l*, pivoted to the combustion-chamber. The air supplied to the lamp under pressure acts on the surface of the oil in the reservoir 130

a through the lower end of the air-passage f, thereby forcing the oil up the pipes 8 and 19, and it passes through the coil 4 into the main passage of the body, from whence it issues 5 through the nozzle 6, thoroughly spraying and intermingling with the oil which issues from the nozzle 7.

It will be observed that by reason of the oil-pipes 8 and 19 being without seam or joint 10 and the reservoir a being made both air and oil tight, the oil cannot possibly escape from said reservoir except through the upper ends of said pipes 8 and 19, and there it is immediately consumed. This is an important feature of construction in lamps of this description, all danger from leaking oil being thereby avoided.

Having now described my invention, what I claim, and desire to secure by Letters Patent, 20 is—

1. In a spray-lamp, in combination, an outer air-nozzle, an oil-nozzle fitted in the air-nozzle as a valve to shut off and regulate the supply of air, a valve located in the oil-nozzle 25 to shut off and regulate the supply of oil, and a handle connected to the combined oil-nozzle and air-valve and the oil-valve, constructed to actuate the air-valve and the oil-valve successively by a single adjustment of 30 the handle.

2. In a spray-lamp, the combination, with an outer air-nozzle, an inner oil-nozzle arranged to act as a valve to the air-nozzle, and a valve located in the oil-nozzle, of a handle 35 and connection between the handle and the oil-nozzle and the oil-valve, whereby it is caused to first move the oil-nozzle away from the air-nozzle, and then the oil-valve away from the oil-nozzle, when turned in one direction, and to first close the oil-valve in the oil-nozzle, and then the oil-nozzle in the air-nozzle when turned in the opposite direction.

3. In a spray-lamp, in combination, an oil-reservoir having the body of the lamp attached thereto, an air-nozzle secured to the 45 top of the body, a straight oil-pipe passing down through the body into the oil contained in the reservoir, an oil-nozzle on the top of the oil-pipe fitted as an air-valve in the air-nozzle, and a handle passing through the body and connected to the oil-pipe for adjusting it relatively to the air-nozzle.

4. In a spray-lamp, in combination, an oil-reservoir having the body of the lamp attached thereto, an air-nozzle secured to the 55 top of the body, a straight oil-pipe passing down the body into the oil contained in the reservoir, an oil-nozzle on the top of the oil-pipe fitted as an air-valve in the air-nozzle, a handle passing through the body and connected to the oil-pipe, a valve in the oil-nozzle carried by a rod extending up the oil-pipe, and connection between the lower end of the valve-rod and the handle.

5. The combination, with a spray-lamp comprising an oil-tank, a body attached thereto and provided with an outer air-nozzle, and an

inner oil-nozzle on the end of a pipe passing down the body into the oil contained in the oil-tank, of a relighter composed of a wick-tube containing a wick in close proximity to the air-nozzle, and a pipe independent of the oil-nozzle-supply pipe joined to the wick-tube and passing down into the oil in the oil-tank.

6. In a spray-lamp, in combination, an oil-tank, a lamp-body attached thereto having two vertical passages, an air-nozzle at the upper end of one of the passages, an oil-nozzle on the end of a pipe passing through this passage into the oil in the oil-tank, an air-supply connection joined to the other passage, a heating-coil arranged above the air-nozzle and connected at one end to the air-supply passage and at its other end to the passage in communication with the air-nozzle, 85 a pipe passing through the air-supply passage into the oil in the oil-tank, and a wick-tube joined to the upper end of this pipe.

7. In a spray-lamp, the combination, with 90 an outer air-nozzle, and an inner oil-nozzle arranged to act as a valve to the air-nozzle, of a handle connected to the oil-nozzle, and an adjustable guide-pin connected with the oil-nozzle, by means of which the retraction of 95 the oil-nozzle in the air-nozzle is governed.

8. In a spray-lamp, the combination, with an outer air-nozzle, and an inner oil-nozzle arranged to act as a valve to the air-nozzle, a valve located in the oil-nozzle, of a handle connected to the oil-nozzle and the oil-valve, and an adjustable stop for the handle, by means 100 of which the retraction of the oil-valve in the oil-nozzle is governed.

9. In a spray-lamp, the combination, with 105 an outer air-nozzle, an inner oil-nozzle arranged to act as a valve to the air-nozzle, and a valve located in the oil-nozzle, of a handle connected to the oil-nozzle and the oil-valve, an adjustable guide-pin for governing the 110 movement of the oil-nozzle, and an adjustable stop for governing the movement of the oil-valve.

10. In a spray-lamp, in combination, a body having a vertical passage, an air-nozzle at the 115 upper end of the passage, an oil-pipe provided with a nozzle located in the passage, a cam secured to the oil-pipe, a pin projecting into the cam from the body, whereby the vertical movement of the oil-pipe is controlled, and a 120 handle provided with a stem passing through the body and by means of which the cam is rotated.

11. In a spray-lamp, in combination, the body 1, the air-nozzle 6, the oil-pipe 8, provided with the oil-nozzle 7, the cam 9, provided with gear-teeth, the eccentric-pin 125 engaging with the cam 10, the handle 24, and the stem 29 of the handle, provided with gear-teeth meshing with the teeth on the cam. 130

12. In a spray-lamp, in combination, the body 1, the air-nozzle 6, the oil-pipe 8, provided with the oil-nozzle 7, the cam 9, provided with gear-teeth, the eccentric-pin 10,

engaging with the cam, the handle 24, its stem 29, gearing with the teeth on the cam, the valve-rod 14, and connections 12 13 15 16 between the cam and the oil-valve rod.

5 13. In a spray-lamp, in combination, the body 1, the air-nozzle 6, the oil-pipe 8, provided with the oil-nozzle 7, the cam 9, provided with gear-teeth, the eccentric-pin 10 on the oil-pipe, engaging with the cam, the handle 24, its stem 29, provided with gear-teeth meshing with the teeth on the cam, the valve and rod 14, connections 12 13 15 16 between the valve-rod and the cam, and the adjustable stop 27 on the handle.

15 14. In a spray-lamp, in combination, the body 1, provided with the air-passage *f*, the coil 4, the combustion-chamber 2, the branch

pipe *g*, connecting the passage *f* with the coil 4, and the sleeves 5 5, provided with right and left handed screw-threads.

15. In a relighting device for spray-lamps, in combination, the body 1, having a flange *i*, the wick-tube 20, extending through the flange *i*, the valve 21, the piece 18, provided with the valve-seat, the pipe 19, for supplying oil to the wick, and the jam-nut 22 at the junction of the wick-tube with the flange *i*.

In witness whereof I have hereunto set my hand, at New York, county and State of New York, this 10th day of July, 1888.

ALFRED SHEDLOCK.
